(57) **CLAIM**

The ornamental design for a wraparound package, as shown and described.

DESCRIPTION

FIG. 1 is a perspective view of the wraparound package showing our new design;

FIG. 2 is a front view, the rear view being a mirror image thereof;

FIG. 3 is a side view, the opposite side being a mirror image thereof;

FIG. 4 is a top view thereof; and,

FIG. 5 is a bottom view thereof.

The broken line portions of the drawings are for illustrative purposes only and form no part of the claimed design.
